(No Model.)

S. ROGERS.
WIRE MAT.

No. 408,047.

Patented July 30, 1889.

UNITED STATES PATENT OFFICE.

SEYMOUR ROGERS, OF BEAVER FALLS, PENNSYLVANIA, ASSIGNEE TO H. W. HARTMAN, OF SAME PLACE.

WIRE MAT.

SPECIFICATION forming part of Letters Patent No. 408,047, dated July 30, 1889.

Application filed July 5, 1888. Serial No. 279,063. (No model.)

To all whom it may concern:

Be it known that I, SEYMOUR ROGERS, a citizen of the United States, and a resident of Beaver Falls, in the county of Beaver and State of Pennsylvania, have invented certain new and useful Improvements in Wire Mats, of which the following is a specification.

My invention has reference to wire door-mats; and it consists of certain improvements, all of which are fully set forth in the following specification and shown in the accompanying drawings, which form a part thereof.

Door-mats have heretofore been made of steel wire woven or interlaced in such a manner as to produce a substantial body well adapted to the purpose for which it is designed. Such mats, however, have had the objection that they were bounded by a rigid frame to keep the flexible center in shape, and the rigidity of this frame prevented any possibility of rolling the mat up for transportation or other purposes.

The object of my invention is to so form the mat and the frame of flexible or steel wire that the same shall not only be flexible, with capacity for being rolled up, but so as to present a more ornamental appearance with a cheap construction.

The details of my invention are fully shown in the drawings, in which—

Figure 1 is a plan view representing my improved mat, a portion of which figure shows the exact construction and coupling of the wire, and the remainder of the outline being indicated in dotted lines. Fig. 2 is a cross-section of same on line X X. Fig. 3 is a sectional plan view of same on line Y Y of Fig. 2, and with the intermediate coils of wire removed to illustrate the staple or hinge wires. Fig. 4 is an end view of my mat rolled up, (details of wire not shown,) and Fig. 5 is a perspective view of the splice-tube.

The body C of the mat is made up of transverse parallel coils A A of spring steel or other suitable wire, and arranged side by side and interlocking, as shown in Figs. 1 and 2, and said coils are connected together, with capacity for flexibility, by means of the staple-shaped hinge-rods B. These rods B have a flat bend in the middle, as at b, and after being pushed through the interlocked coils of

three adjacent coils A, so as to hinge them together, the ends b' thereof are bent over, as shown in Figs. 1 and 3, to lock or secure them firmly in place. In practice it is customary to push these hinge-rods B in alternately from opposite sides of the body of the mat, and thus more uniformly distribute the ends b b' and make the body of the mat of uniform strength and durability. It is evident that these hinge-rods may be single or unbent rods, as shown at G, Fig. 1; but there is less work required and more strength gained in making the mat with them in the form shown. This body portion of the mat, it will be seen, is made by tying or locking the adjacent coils together by the hinge-rods, and the coils or wires forming such body part are not of themselves interlaced or interwoven, as is customary in other makes of mats of this class and when flexibility is not required.

The body part C so formed is bounded on its edges with coils D, of similar appearance and construction, which are twisted into or interwoven with the lateral terminals of the body-coils A, as clearly shown in Fig. 1.

It will be seen by examining Fig. 1 that the bounding-coils D are interlooped with the hinge-rods, and that these rods B and G hold the bounding-coil D to the body part, increasing the durability without increase in labor of production. In this connection it is evident that a decided advantage is to be had by inserting the staple-shaped hinge-rods B alternately from opposite sides, as they present the looped ends b on each side of the mat to interloop with the bounding-coils. It is preferable to make the bounding-coils D in two parts and secure them to the sides of the mat, as above set out, and then take the extending ends d (see dotted lines, Fig. 1) and bend them toward each other, forming graceful rounded corners F, and connect the ends d together by a splice-tube E or otherwise, as desired. This splice-tube would extend into the coils of each end and will conceal the ends of such coils, so as to give the appearance of a continuous coil all around the mat. These splice-tubes are preferably made of light sheet metal, and are slotted, as at e, to receive the curved sides of the adjacent coils A, (see Fig.

2,) and thus hold itself, as well as the coils it supports, in a fixed relation with respect to the body-coils. The coils of the ends of the bounding-coils D are connected or hinged to 5 the adjacent body-coils A by the hinge-wire G, as in the case of the wires B and body-coils, and the ends g are bent over to secure said rod from being removed.

It will be observed that the binding-coils D 10 at the sides of the body part C, as well as the ends b of the hinge-rods B, prevent the coils A from shoving together and collapsing the mat, and likewise the splice-tube E acts to perform the function of holding the end coils out 15 and giving an ornamental and light appearance to the mat. It is evident that the splice-tube E might be made solid, if desired; but there would be no object therein, and it would have the objection of weight. The corners F 20 in the construction here shown are very ornamental and extremely durable, and that, too, with a minimum cost.

In carrying out the generic features of my invention the particular method of obtaining 25 the flexibility herein set out may be modified without departing from my invention.

Having now described my invention, what I claim as new, and desire to secure by Letters Patent, is—

30 1. In a wire mat, a body part composed of a series of parallel coils united by hinge-rods, in combination with a bounding-coil made in one or more parts extending entirely around the mat and arranged transversely to the body-coils on two sides of the mat, and in which the hinge-rods are interlooped with the ends of such body-coils and bounding-coils, substantially as set forth.

2. In a wire mat, a body part formed of a 40 series of parallel coils connected together, in combination with a bounding-coil made in one or more parts and arranged transversely to the body-coils and along their ends, and wire rods extending through the body-coils 45 and entirely across the body of the mat and connecting the bounding-coils on diametrically opposite sides of the mat to the body-coils, substantially as set forth.

3. In a wire mat, the body portion formed 50 of a series of parallel coils of wire, combined with a series of staple-shaped hinge-rods connecting the adjacent coils together, and in which said staple-shaped hinge-rods are in-

serted from opposite sides of the mat, substantially as set forth.

4. In a wire mat, the flexible body part composed of wire coils, in combination with a bounding-coil made in one or more parts surrounding the edges of the body part and arranged partly parallel to and partly transverse with respect to the body-coils, and a hinge-wire located at the end of the mat for uniting the parallel portions of the bounding-coil to the end coil of the body part, substantially as set forth.

5. In a wire mat, the body part formed of a series of parallel coils, combined with staple-shaped hinge-rods connecting the parallel coils, and a flexible bounding-coil made in one or more parts and arranged transversely 7c to the body-coils, interwoven both with the ends of the said body-coils and looped ends of the staple-shaped hinge-rods, substantially as set forth.

6. In a wire mat, a body part formed of 75 wire-work, combined with bounding-coils D, extending along two diametrically-opposite edges of the body part and bent around the corners toward each other and made to meet, or substantially meet, on the other edge, the body part, a splice tube or piece E, arranged partly within each of the ends of the bounding-coils, and a connection between the said bounding-coils on each side of the splice-tube and the body part, substantially 85 as set forth.

7. In a wire mat, the body part formed of parallel coils of wire united by hinge-rods, in combination with bounding-coils D, interlaced with the ends of the body-coils, and having 90 their end portions parallel to the ends of the body part and secured thereto by connecting-rod or hinge-wire G, substantially as set forth.

8. In a wire mat, the body part formed of 95 parallel coils of wire united by hinge-rods, in combination with bounding-coils D, interlaced with the ends of the body-coils, and having their end portions parallel to the ends of the body part and secured thereto by connecting-rod or hinge-wire G and united by a splice-tube E, substantially as set forth.

SEYMOUR ROGERS.
